United States Patent Office

Des. 224,106
Patented July 4, 1972

224,106

PRESSURE REGULATOR

Frank Baranowski, Jr., 7 Pine St.,
Lynnfield Center, Mass. 01940

Filed Dec. 15, 1970, Ser. No. 26,501

Term of patent 14 years

Int. Cl. D23—01

U.S. Cl. D23—21

Fig. 1.

Fig. 2.

Fig. 3.

FIG. 1 is a top plan view of a pressure regulator showing my new design;

FIG. 2 is a side elevational view thereof; and

FIG. 3 is a bottom view thereof.

I claim:

The ornamental design for a pressure regulator, as shown.
